CLAIM

The ornamental design for a humidifier with wireless speaker, as shown and described.

DESCRIPTION

FIG. 1 is a first perspective view of a humidifier with wireless speaker showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the selected portion 9 in FIG. 1; and,

FIG. 10 is an enlarged view of the selected portion 10 in FIG. 1.

The broken lines shown in the drawings depict portions of the humidifier with wireless speaker that form no part of the claimed design. The dot dash broken lines encircling portions of the humidifier with wireless speaker in FIG. 1 and illustrated in the enlarged views of FIG. 9 and FIG. 10 form no part of the claimed design.
